Specification of Letters Patent.

Patented Oct. 13, 1914.

Application filed April 6, 1912. Serial No. 689,017.

To all whom it may concern:

Be it known that we, RICHARD K. LE BLOND and WILLIAM F. GROENE, citizens of the United States of America, and residents 5 of Cincinnati, county of Hamilton, and State of Ohio, have invented certain new and useful Improvements in Lathes, of which the following is a specification.

This invention is an improvement in lathes 10 and has for an object to produce a lathe having improved means for preventing the feed drive and the traverse drive of the tail-stock or tool-carrying member from being simultaneously thrown into operation.

15 A further object is to produce a lathe having new and improved means for preventing the traverse drive mechanism from operating the hand or pilot wheel of the lathe and thereby eliminating the danger 20 ordinarily encountered in lathes, due to the whirling of the pilot wheel when the traverse drive mechanism is thrown into operation.

25 A further object is an improved lathe which is more effective in operation and is easier to manipulate than other lathes known to us.

These and other objects we attain by 30 means of a lathe embodying the features herein described and illustrated.

In the drawings accompanying and forming a part of this application, Figure 1 is 35 a fragmental sectional plan view along the broken line 1—1 of Fig. 3; Fig. 2 is a fragmental sectional view along the line 2—2 of Fig. 3; Fig. 3 is a fragmental sectional view along the broken line 3—3 of Fig. 1; Fig. 4 is a fragmental sectional view 40 along the broken line 4—4 of Fig. 1 and Fig. 5 is a fragmental sectional view along the line 5—5 of Fig. 1.

The lathe herein illustrated as an embodiment of our invention includes the usual frame 5, the usual head-stock and chuck, 45 which are not herein shown, and a tool-carrying element or tool-slide 6, which is capable of moving along ways or shears 8 provided on the frame 5.

The tool-slide 6 is reciprocated along its 50 ways by means of two independent power shafts 9 and 10; the latter of which is included in a power transmission mechanism for the tool-slide which is ordinarily termed the "feed drive", while the other forms a 55 part of a power transmission mechanism

which is sometimes termed the "traverse drive" and which is employed in the preliminary operation of moving the tool up to the work on the head-stock, and also in the operation of withdrawing the tool from 60 the work.

In addition to the feed and traverse drive mechanism the lathe is provided with the usual pilot wheel 14 which is mounted on a shaft forming a part of the feed-drive and is employed in shifting the tool-slide in the final operation of adjusting the tool to the work on the head-stock. The feed drive and the traverse drive mechanisms each coöperate with a rack 11, in actuating the tool-slide and each includes a pinion 12, which meshes with the rack, and an actuating gear 13, which is shown as integrally formed with the pinion 12. Means are provided for preventing the traverse drive mechanism from being thrown into operation while the feed drive mechanism is operating, and vice versa, for preventing the feed drive from being thrown in while the traverse mechanism is in operation, so that the pilot wheel 14, will not be spun around at a dangerous speed while the traverse mechanism is in operation. The means illustrated for accomplishing this, includes a single handle 15, which is capable of simultaneously actuating two separate clutch devices so that one transmission mechanism is rendered operative and the other is rendered inoperative. In the apparatus illustrated, the handle 15 has the additional function of shifting the clutch device, forming a part of the traverse mechanism so that the tool-slide may be reversed in its movement along the ways and may be rapidly moved up to or withdrawn from the work on the head-stock. 95

The shaft 9 of the "traverse drive" extends along the frame parallel to the ways 8, and is provided with any suitable actuating means, such as are ordinarily employed and are usually located at the head-end of the lathe. A bevel pinion 16 is splined onto the shaft 9 so that it is capable of being rotated by the shaft, and at the same time moving longitudinally of the shaft. An elongated hub, or, laterally projecting sleeve 17 is shown as integrally formed with the pinion 16 for the purpose of increasing the bearing surface between it and the shaft, and also for providing adequate bearing surface between the pinion 110

and an extension 18, which is provided on the tool-slide and in which the sleeve 17 is journaled. A bevel gear 20 meshes with the pinion 16 and is rigidly mounted on one end of a shaft 21, which is journaled in a suitable bearing provided in the body of the tool-slide, and on the other end of which a second bevel gear 22 is rigidly mounted. The gear 22 is continuously in mesh with two oppositely disposed bevel gears 23 and 24, which are loosely mounted on a shaft 25 and are located diametrically opposite to each other, with respect to the gear 22 so that they are driven in opposite directions by it.

A clutch member 26 is splined onto the shaft 25 and is adapted to be moved along the shaft 25 for the purpose of operatively connecting it to one or the other of the gears 23 and 24. Each lateral face of the clutch member 26 is provided with a series of teeth 26' which are adapted to coöperate with similar teeth formed on one lateral face of each of the gears 23 and 24 and to thereby operatively lock one of the gears to the shaft 25 when the clutch member 26 is moved into engagement with it. The shaft 25 is suitably journaled within the body of the tool-slide and is provided at its inner end with a rigidly mounted gear 27, which meshes with the gear 13 and therefore actuates the pinion 12 which meshes with the rack. With this arrangement the tool-slide is moved in one direction along its ways when the clutch member 26 is in engagement with the bevel gear 23 and it is moved in the other direction when the clutch member is in engagement with the gear 24, since the rotation of the shaft 25 and consequently of the gears 27, 13 and 12 is reversed when the clutch member is disconnected from one of the gears 23 and 24 and is moved into engagement with the other. The rotation of the pinion 12 causes the pinion to roll along the rack 11 and this causes the tool-slide to move along its ways with the pinion.

The "feed drive" mechanism includes the shaft 10 which extends parallel to the ways 8 and consequently to the shaft 9. A worm 28 is shown splined to the shaft 10 and meshing with a worm wheel 29 which is rigidly mounted on a shaft 30, journaled in the body of the tool-slide. The worm 28 is located between two opposed faces provided on the tool-slide body so that it is moved along the shaft 10 with the tool-slide and is prevented from moving laterally with relation to the wheel 29. A gear 31 is loosely mounted on the shaft 30 and is adapted to be operatively connected to it by means of a clutch device, which as herein shown, consists of teeth 29' formed on the lateral face of the wheel 29 and coöoperating teeth 31' integrally formed with the gear 31, the gear 31 being shiftable longitudinally of the shaft

for the purpose of moving its teeth 31' into and out of engagement with the teeth 29'. The teeth of the gear 31 are of such length that they are not thrown out of mesh with the teeth of a coöperating gear 32, when the gear 31 is shifted longitudinally for the purpose of moving into and out of clutching engagement with the worm wheel 29. The gear 32 is rigidly mounted on a shaft 33, which is provided with a gear 34 herein shown formed integrally with the shaft 33, its teeth being cut in the surface of the shaft. A gear 35 meshes with the gear 34 and is loosely mounted on a sleeve 36, which surrounds a shaft 37, and is capable of moving longitudinally of the shaft. A gear 38 is mounted on the sleeve so that it is capable of rotating relatively thereto, but it is prevented from moving along the sleeve by means of a shoulder 39, formed on the sleeve and located on one side of it, and a collar 40 located on the other side of it and secured to the sleeve by any suitable means, such as a set screw. One lateral face of the gear 38 is provided with teeth 41, which coöperate with teeth 42, formed on the lateral face of an elongated hub, with which the gear 35 is provided. The sleeve 36 is capable of being moved along the shaft 37 to such an extent that the gear 38 shifts sufficiently to move its teeth 41 into and out of engagement with the teeth 42 of the gear 35. The gear 35 is prevented from moving longitudinally with the sleeve 36 by means of a collar 43, mounted on the shaft 33, and an abutting surface 44, provided on a convenient portion of the tool-slide body. The collar 43 is located adjacent to the gear 34 so that it forms a shroud for its teeth and consequently engages the ends of the teeth of the gear 35 and prevents the gear 35 from moving in one direction, while the surface 44 prevents it from moving in the other direction, relatively to the gear 34. The gear 38 meshes with the gear 27, on the shaft 25 and is provided with elongated teeth for the purpose of continuing it in mesh with the gear 27, while it is in the different longitudinal positions.

When the gear 31 is shifted so as to lock it to the worm wheel 29 and the gear 38 is shifted so as to lock it to the gear 35 the "feed drive" transmission mechanism is rendered operative and moves the tool-slide along its ways in the following manner. The shaft 10 is driven by suitable means such as is ordinarily employed in lathes and drives the worm 28, which in turn drives the worm wheel 29. The worm wheel drives the shaft 33 through the agency of the gears 31 and 32, and the gear 34, cut into the shaft 33, drives the gear 27 through the agency of the interlocked gears 35 and 38. The gear 27 drives the gear 13 and the pinion 12 and thereby causes the pinion to roll along

the rack 11 and to move the tool-slide along its ways. The gear 27 is rigidly mounted on the shaft 25, and forms a part of the "traverse drive" mechanism, as has been described, but the arrangement is such that the clutch member 26, renders the "traverse drive" mechanism inoperative when the sleeve 36, is moved to such a position that the gear 38 is locked to the gear 35.

10 The sleeve 36 is actuated by the handle 15 which is rigidly mounted on the shaft 37 and is provided with a radially extending flange 46 on which teeth 46', having inclined lateral faces, are mounted. The teeth are located on a lateral face of the flange 46 and are adapted to engage grooves 47' formed in the lateral face of a similar flange 47, which is located on the end of the sleeve 36. The sleeve is prevented from turning with the shaft 37 by any suitable means, such for example, as a stationary key 48 which engages a groove formed in the bearing face surrounding the sleeve and which projects into a slot formed in the sleeve. With this arrangement the sleeve will be shifted longitudinally along the shaft 37 when the handle 15, and consequently the shaft is turned so as to cause the inclined faces of the teeth 46' to ride up the inclined faces of the grooves 47' and in this manner force the flange 47 away from the flange 46. This longitudinal motion of the sleeve 36 is resisted by a coiled spring 51, which surrounds the shaft 37 and is located between the inner end of the sleeve 35 and a collar 52 rigidly mounted on the shaft. The teeth 46' are so constructed that they will shift the sleeve 36 longitudinally a sufficient amount to disengage the teeth 41, of the gear 38, from the teeth 42, of the gear 35 and thereby permit the gear 35 to rotate loosely on the sleeve without transmitting power, when the handle is turned in either direction from the normal position. The spring 51 also operates to shift the sleeve 45 back to its normal position so that the teeth 41 and 42 are interlocked, when the handle 15 is turned to its normal position in which the teeth 46' enter the grooves 47'. The handle 15 is also capable of actuating the clutch member 26 for the purpose of controlling the operation of the "traverse drive" mechanism. This is accomplished through the agency of a worm 53 which is mounted on, or formed integrally with, the shaft 37 and meshes with a worm-rack or yoke 54. The yoke is capable of moving longitudinally in response to the rotation of the worm 53 and is provided with a finger 55 which engages the clutch member 26.

60 The worm 53 and the yoke 54 are so arranged that the yoke and consequently the clutch member 26 occupy an intermediate position when the handle 15 is in the normal position, or that position in which the teeth 46 enter the grooves 47. With this arrangement

ment the clutch member 26 renders the "traverse drive" mechanism inoperative when the "feed drive" mechanism is operative and the yoke shifts the clutch member 26 into engagement with one of the gears 23 or 24, when the handle 15 is turned in one direction or the other from its normal position, and after the "feed drive" mechanism has been rendered inoperative, by the disengagement of the gears 35 and 38. This causes the "traverse drive" mechanism to move the tool-slide toward the head-stock, in case the clutch member is in clutching engagement with the gear 23, and away from the head-stock if the clutch member is in engagement with the gear 24. The pitch of the worm 53 and the altitude of the teeth 46' are so proportioned that the disengagement of the gears 35 and 38 and the engagement of the clutch member 26 with one of the gears 23 and 24 are approximately simultaneous operations and consequently it is impossible to render the "traverse drive" mechanism operative while the "feed drive" mechanism is in operation. The first movement of the handle 15, while it is being turned back to its normal position, renders the "traverse drive" mechanism inoperative by shifting the clutch member 26 to an inoperative position and the handle then renders the "feed drive" mechanism operative by coupling the gears 35 and 38 together, as has been described. These two operations are also substantially simultaneous and therefore prevent the "feed drive" mechanism from being thrown into operation while the "traverse drive" mechanism is in operation. While the "traverse drive" mechanism is in operation the gear 38 rotates loosely on the sleeve 36 and is therefore incapable of imparting the rotation of the gear 27 to the shaft 33 on which the pilot wheel 14 is mounted. Under these conditions there is no danger of the pilot wheel being turned at a high velocity during the operation of the traverse mechanism.

One of the features of our invention is a new and improved means for automatically stopping the tool-slide as it moves toward the rear end of the ways while being actuated by the "traverse drive" mechanism. The means herein illustrated consists of a vertically extending rack 56 which engages a gear 57 mounted on, or integrally formed with the shaft 37, and normally projecting downwardly below the bottom of the body portion of the tool-slide so that its lower end may be engaged by a lug or stop 58, located on the frame 5 of the lathe. The projecting end of the rack is beveled and the stop 58 is inclined so that the rack will be moved upwardly when it contacts with the stop. This upward motion of the rack will turn the shaft 37 and consequently shift the yoke 54. The stop is so designed that it 130

imparts sufficient motion to the rack to shift the yoke, so as to move the clutch member 26 out of engagement with the teeth on the gear 23. The stop is also of such length that 5 the momentum of the tool-slide can not carry the pin past it after the traverse mechanism has been rendered inoperative. If desired, the stop may be of such height that it will not only render the traverse mechanism inoperative but will also render the 10 "feed drive" mechanism operative by moving the gear 38 into engagement with the gear 35 and thereby reversing the motion of the tool-slide. It will also be understood 15 that an additional stop may be provided for checking the forward motion of the tool-slide and that the stop may be adjustably mounted on the frame so that it may be employed in stopping the tool-slide at various 20 positions along the ways.

We have also provided improved means for shifting the gear 31 into and out of locking engagement with the wheel 29. The means illustrated consists of a bar or shaft 25 59 which is provided at one end with the handle 59' and at the other with a worm 60 which engages a yoke 61 capable of reciprocating as the handle is turned. A finger 62 is provided on the yoke and engages an annular groove formed in the gear 31. With 30 this arrangement the gear 31 may be moved into locking engagement with the wheel 29 by turning the handle in one direction and it may be withdrawn from engagement 35 with the wheel by turning the handle in the other direction. This provides means for controlling the operation of the feed drive mechanism which is entirely independent of the handle 15. We have provided means for 40 holding the handle 59', and consequently the yoke 61, in either of their extreme positions. The means illustrated comprises a cam 63, mounted on the shaft 59, and a coöperating plunger 64, which is continually held in 45 contact with the peripheral face of the cam.

Inclined grooves 65 are provided in the peripheral face of the cam for receiving the end of the plunger and these grooves are so located that one or the other will coöperate 50 with the plunger in holding the shaft against motion when the handle is turned to one or the other of its extreme positions.

The handle 59' and the clutch mechanism operated by it are capable of rendering the 55 "feed drive" mechanism inoperative when it is desired to manually shift the tool-slide by means of the pilot wheel. The handle therefore coöperates with the other mechanisms employed in producing three separate 60 rate means for shifting the tool-slide; that is, the hand operated means, the shaft 10 or the "feed drive" and the shaft 9 or the "traverse drive." While the handle 59' can be employed in starting and stopping the 65 "feed drive," it cannot render the "feed

drive" effective as a driving agent for the tool-slide unless the handle 15 is in the normal position and the "traverse drive" mechanism is inoperative.

A feature of our invention is the arrangement of the power transmission mechanism so that the teeth 31' may remain in locking engagement with the teeth 29' without in any way interfering with the operation of the "traverse drive" mechanism. In 70 other words the handle 59' may be turned to the normal operative position, so as to lock the gear 31 to the gear 29, while the "traverse drive" mechanism is being employed to shift the tool-slide forward and 75 backward along the ways. This arrangement simplifies the operation of the lathe, since it can be controlled almost entirely by the single operating lever 15.

We use the term tool-slide throughout the 85 specification and in the claims with no idea of limiting our invention to the specific form of apparatus illustrated and we wish it to be understood that by the term tool-slide 90 we include all forms of reciprocal tool-carrying elements for lathes or similar machines.

In compliance with the United States 95 patent statutes we have illustrated the preferred embodiment of our invention and described its functions and principles of operation, but we desire it to be understood that various changes, substitutions and modifications may be made without departing from the spirit and scope of our invention 100 as set forth in the appended claims.

What we claim is:

1. In a machine of the character described, a frame having a way provided thereon, a tool slide mounted on the frame and movable along the way, a rack on the frame and paralleling the way, two separate power transmission mechanisms, mounted on the slide, for coöperating with the rack and for independently moving the slide along the way, a separate clutch mechanism for controlling each power transmission mechanism and a single means mounted on the way for controlling the operation of both clutch mechanisms. 110

2. In a machine of the character described, a frame, a tool slide movable along the frame, a feed drive mechanism mounted on the slide, for moving it in one direction along the frame, a reversible traverse drive mechanism mounted on the slide, for moving it in both directions along the frame, and single means, mounted on the slide, for rendering one driving mechanism operative and the other inoperative, and for reversing 120 the traverse drive mechanism.

3. In a machine of the character described, a tool-slide, a frame having ways along which the tool-slide is movable, a rack extending along the ways, a feed drive shaft 130

- and a traverse drive shaft, journaled on the frame and extending along the way, a feed drive mechanism mounted on the slide for coöperating with the rack in moving the slide along the way, a traverse drive mechanism mounted on the slide, for coöperating with the rack in moving the slide along the way, means for operatively connecting said feed drive mechanism to said feed drive shaft, means for operatively connecting said traverse drive mechanism to said traverse drive shaft, and a single device, mounted on the slide, for rendering one mechanism operative and the other inoperative as a moving agent of the slide. 6
4. In a machine of the character described, a tool-slide, a frame along which the slide is movable, a feed drive shaft and a traverse drive shaft journaled on the frame, a feed drive mechanism and a traverse drive mechanism, mounted on the tool-slide, for independently moving the slide along the frame, means for operatively connecting said feed drive mechanism to, and for disconnecting it from, said feed drive shaft, means for operatively connecting said traverse drive to, and for disconnecting it from said traverse drive shaft, and a single lever mounted on the slide, for simultaneously actuating both of said means, and for thereby rendering the one mechanism operative and the other inoperative, as the driving agent of the slide. 10
5. In a machine of the character described, a tool-slide, a frame along which the slide is movable, a feed drive shaft, a traverse drive shaft journaled on the frame, a feed drive mechanism mounted on the slide, a traverse drive mechanism mounted on the slide, means for operatively connecting said feed drive mechanism to said feed drive shaft, means for operatively connecting said traverse drive mechanism to said traverse drive shaft, and a device for simultaneously actuating both of said means. 15
6. In a machine of the character described, a frame having a way provided thereon, a tool-slide mounted on and movable along the way, a rack extending along the way, a feed drive mechanism coöperating with the rack to move the slide along the way, a reversible traverse drive mechanism coöperating with the rack to move the slide along the way, and a single means for rendering one mechanism operative and the other inoperative as the driving agent of the slide and for reversing the direction of the traverse drive mechanism. 20
7. In combination in a machine of the character described, a tool-slide, a frame provided with a way along which said slide is movable, a rack mounted on the frame, a traverse drive mechanism, mounted on the slide, for coöperating with the rack and for moving the slide along the way, a feed drive mechanism, mounted on the slide, for co-operating with the rack and for moving the slide along the way, a clutch, included in the traverse drive mechanism, for rendering it operative or inoperative in moving the slide, a clutch, included in the feed drive mechanism, for rendering it operative or inoperative, a longitudinally reciprocal sleeve, mounted on the slide, for controlling said last-mentioned clutch, a worm for controlling the first-mentioned clutch, a shaft extending through said sleeve, for actuating said worm, and a single handle for actuating the sleeve and the shaft. 25
8. In combination in a lathe, a tool-slide, a frame having ways along which the tool-slide is capable of being moved, separate transmission mechanisms for actuating said tool-slide, a separate clutch device for controlling the operation of each mechanism, a shaft for actuating one clutch device, a longitudinally reciprocating member for actuating the other clutch device and a single device for actuating said shaft and said member. 30
9. In combination in a machine of the character described, a tool-slide, a frame having ways along which the slide is adapted to move, a feed-driving agent, a traverse-driving agent, a feed drive transmission mechanism mounted on said slide and operatively connected to said feed-driving agent, a traverse drive mechanism mounted on said slide, and operatively connected to said traverse drive agent, a separate clutch device for controlling each mechanism, means for actuating each clutch device, and a single handle for actuating both of said means. 35
10. In combination in a lathe, a tool-slide, a frame having ways along which said tool-slide is capable of moving, two separate transmission mechanisms for moving the tool-slide along the ways, a rack, an intermeshing pinion and an actuating gear for the pinion common to each mechanism, a separate clutch device for controlling the operation of each mechanism and means for simultaneously actuating each clutch device to operatively connect said rack, pinion and actuating gear to one of the mechanisms and to disconnect the other. 40
11. In a lathe, a tool-slide, a frame having ways along which the tool-slide is adapted to move, a transmission mechanism for the tool-slide, including a shaft, oppositely rotated gears mounted on the shaft and a clutch member for operatively connecting one or the other of the gears with the shaft, a second transmission mechanism, including two interlocking gears, one of which is longitudinally shiftable, and a longitudinally shiftable sleeve on which said gears are mounted, and means for shifting said clutch member to connect one or the other of said oppositely rotated gears with said shaft and 45

for simultaneously shifting said sleeve to disengage said interlocking gears.

12. In combination in a machine of the character described, a tool-slide, a frame having a way along which the slide is movable, a transmission mechanism, for shifting the slide along the way, including a shaft, oppositely rotated gears loosely mounted on the shaft, a clutch mechanism for operatively connecting one or the other of said gears to the shaft, a second transmission mechanism, for shifting the slide along the way, including two interlocking gears, one of which is longitudinally shiftable, a single handle for shifting said clutch mechanism and said shiftable gear, means, actuated by the handle, for shifting the clutch mechanism into engagement with one or the other of said loosely mounted gears, and means, actuated by the handle, for shifting the shiftable gear while the clutch mechanism is in the neutral position.
13. In a lathe, a tool-slide, a frame having ways along which the tool-slide is adapted to reciprocate, a transmission mechanism for the tool-slide including a shaft, oppositely rotated gears loosely mounted on the shaft, a clutch member for operatively connecting one or the other of said gears with the shaft, a second transmission mechanism for the tool-slide, including two interlocking gears, one of which is longitudinally shiftable, in combination with a longitudinally shiftable sleeve on which said interlocking gears are loosely mounted, a rotatable shaft extending through said sleeve and operatively connected to said clutch member and an operating handle mounted on the shaft, for rotating the shaft and reciprocating the sleeve.
14. In combination in a machine of the character described, a tool slide, a frame having a way along which the slide is adapted to move, a transmission mechanism, mounted on the slide, for moving it along the way, a second transmission mechanism, mounted on the slide, and including means for reversing the motion of the slide, a device for actuating the reversing means, means for rendering the first-mentioned transmission mechanism inoperative, and a single operating handle, mounted on the slide, for controlling the operation of both of said means.
15. In combination in a machine of the character described, a tool-slide, a frame provided with a way along which said slide is movable, a feed drive shaft and a traverse drive shaft mounted on the frame, a feed drive transmission mechanism, operatively connected to the feed drive shaft and mounted on the slide, and including a shaft, a gear rotatably mounted on the shaft and a clutch member for operatively connecting the gear to the shaft, a traverse drive mechanism mounted on the slide, operatively connected

to the traverse drive shaft and including interlocking gears, one of which is longitudinally shiftable, with relation to the other, and means, mounted on the slide, for simultaneously actuating the clutch member and for shifting the shiftable gear.

16. In combination in a machine of the character described, a movable tool-carrying member, a frame provided with a way along which the member is movable, separate transmission mechanisms, mounted on the member, for independently controlling its motion along the way, and a device, actuated by the motion of the member along the way, for rendering one mechanism inoperative and the other operative.

17. In combination in a machine of the character described, a frame provided with a way extending longitudinally thereof, a tool-carrying member movable along the way, a rack on the frame and extending along the way, a feed drive mechanism mounted on the tool-carrying member and cooperating with said rack in moving the member in one direction along the way, a reversible traverse drive mechanism mounted on the member, for moving the member in both directions along the way, a clutch device for controlling the operation of the feed drive mechanism, a clutch mechanism for reversing the traverse drive mechanism and for rendering it operative and inoperative as a driving agent of the tool-carrying member, and a single means for controlling the clutch device and the clutch mechanism, whereby one driving mechanism is rendered ineffective when the other is rendered effective as the driving agent of the member.

18. In combination in a lathe, a movable tool-slide, a feed drive and a traverse drive mechanism for the tool-slide and means actuated by the tool-slide for rendering the traverse drive inoperative and for rendering the feed drive operative.

19. In combination in a lathe, a movable tool-slide, two separate transmission mechanisms for the tool-slide, a separate clutch device for controlling the operation of each mechanism, and means actuated by the motion of the tool-slide for simultaneously actuating both of said clutch devices.

20. In combination in a machine of the character described, a frame having a way provided thereon, a movable tool-carrying member movable along the way, a feed drive mechanism mounted on the member for propelling it along the way, a traverse drive mechanism mounted on the member, for propelling it along the way, a separate clutch for controlling the operation of each mechanism, a device mounted on the member for actuating said clutches to render one mechanism inoperative and the other operative as a propelling agent for the member, and means mounted on the frame, for

- engaging said device, and for thereby actuating said clutches.
21. In combination in a lathe, a tool-slide, a frame having a way along which said tool-slide is capable of moving, a transmission mechanism for the tool-slide having a clutch for controlling its operation, a shaft for actuating the clutch, a pin carried by the tool-slide and having a rack engaging teeth on the shaft, and means for engaging said pin during the motion of the tool-slide for actuating it to rotate the shaft and shift the clutch.
22. In combination in a lathe, a tool-slide, a frame having ways along which the tool-slide is adapted to move, a transmission mechanism for actuating the tool-slide and having a clutch for controlling its operation, a yoke for actuating said clutch, a rotatable shaft having a worm for actuating said yoke, a reciprocal pin having a rack engaging teeth on said shaft, and means mounted on the frame for engaging the pin and actuating the shaft.
23. In a machine of the character described, a tool-carrying member, a frame having a way along which the member is adapted to move, a transmission mechanism mounted on the member and including means for reversing the motion of the member along the way, a clutch device for rendering the transmission mechanism operative and inoperative, and for reversing the motion of the member, a second transmission mechanism mounted on the member, a clutch device for rendering said second transmission mechanism operative or inoperative, as a propelling agent for the member, and means, mounted on the member, for controlling the operation of both of said clutch devices, and for rendering one mechanism inoperative as a propelling agent of the member, while the other is operative.
24. In combination in a machine of the character described, a tool-carrying member, a frame having a way along which the member is movable, two separate power shafts mounted on the frame, two transmission mechanisms mounted on the member, each mechanism being operatively connected to one of said shafts, means mounted on the member, for controlling the operation of each mechanism, and means, actuated by the motion of the member along its ways, for actuating said first-mentioned means to render one of said mechanisms ineffective and the other effective, in propelling the member along the way.
25. In combination in a lathe, a tool-slide, a frame having ways along which said tool-slide is adapted to move, two separate transmission mechanisms for the tool-slide, a single device for controlling the operation of each mechanism, and means actuated by
- the motion of the tool-slide for actuating said device to render one of said mechanisms ineffective and the other effective.
26. In combination in a lathe, a tool-slide, a frame having ways along which the tool-slide is adapted to move, two separate transmission mechanisms for the tool-slide, and a rack, an intermeshing pinion, and an actuating gear for the pinion, common to each transmission mechanism.
27. In combination in a lathe, a tool-slide, a frame having ways along which the tool-slide is adapted to move, two separate transmission mechanisms for the tool-slide having a rack, a pinion meshing with the rack, and an actuating gear for the pinion, common to each mechanism, and a single actuating means for controlling the operation of each mechanism.
28. In combination in a machine of the character described, a tool-carrying member, a frame having a way along which the member is movable, two separate power shafts mounted on the frame, two transmission mechanisms mounted on the member, each mechanism being operatively connected to one of said shafts, and a single handle, mounted on said member, for controlling the operation of both of said transmission mechanisms, and means, actuated in response to the movement of the carriage along the way, for controlling the operation of said first-mentioned means.
29. In combination in a machine of the character described, a tool-carrying member, a frame having a way formed thereon, along which said member is movable, a rack extending along the way, two separate sets of gears mounted on the member and co-operating with the rack to impel the member along the way, reversing gears included in one set of gears, means for rendering one set of gears operative and inoperative, and for controlling the operation of the reversing gears, means for rendering the other set of gears operative and inoperative, and an interlocking device for controlling the operation of both of said means, so that one set of gears is rendered inoperative while the other is operative.
30. In a machine of the character described, a tool-carrying member, a frame having a way along which the member is movable, two separate transmission mechanisms for shifting the member along the way, a separate clutch device for each mechanism, movable to an operative and an inoperative position, to render its transmission mechanism operative and inoperative, and means whereby one of said mechanisms may be rendered operative while the controlling clutch of the other mechanism is in the operative position.
31. In a lathe, a tool-slide, a transmission mechanism for moving the tool-slide along

- its ways, a clutch device, movable to an operative and an inoperative position to render said mechanism operative and inoperative, a second transmission mechanism for the tool-slide, an interlocking device for rendering one mechanism inoperative while the other is operative and means actuated by the interlocking device whereby said second mechanism may be rendered operative while said 10 clutch device is in the operative position.
32. In a lathe, a tool-slide, a transmission mechanism for moving the tool-slide along its ways, a clutch device movable to an operative and an inoperative position to render 15 said mechanism operative and inoperative, a second transmission mechanism for the tool-slide, a clutch member for controlling the operation of said second mechanism, a clutch mechanism included in said first mentioned 20 transmission mechanism whereby said second mentioned transmission mechanism may be rendered operative while said first mentioned clutch device is in the operative position.
33. In a lathe, a tool-slide, a feed drive transmission mechanism for the tool-slide, a traverse drive transmission mechanism for the tool-slide, a clutch mechanism included in the feed drive and movable to an operative 25 and an inoperative position for rendering the feed drive operative and inoperative, a reversing clutch included in the traverse drive for rendering the traverse drive operative and inoperative and for reversing the 30 motion of the tool-slide and means whereby said traverse mechanism may be rendered operative when the clutch device of said feed drive mechanism is in the operative position.
34. In a lathe, a tool-slide, a feed drive mechanism, a hand drive mechanism and a traverse drive mechanism for shifting the tool-slide along its ways, and a single device for rendering said feed drive and said hand 35 drive mechanisms inoperative when said traverse drive is rendered operative.
35. In a lathe, a tool-slide, three separate transmission mechanisms for shifting the tool-slide along its ways and a single means for rendering two of said mechanisms inoperative and the other operative, whereby the operative mechanism may be reversed without effecting the inoperative mechanisms.
36. In a lathe, a tool-slide, a transmission mechanism for the tool-slide including a shaft, oppositely rotated gears loosely mounted on the shaft and a clutch member for operatively connecting one or the other 40 of said gears to the shaft, a second transmission mechanism for the tool-slide including two interlocking gears one of which is longitudinally shiftable and a single means for simultaneously shifting said clutch member and said longitudinally shiftable gear and 45 for moving said gear faster than said clutch member.
37. In a machine of the character described, a tool-carrying member, a frame having a way along which the member is movable, two separate driving shafts for said member, a separate gear train, actuated by each shaft, for impelling the member along the way, a separate clutch device for rendering each gear train operative or inoperative as an impelling agent for the member, and means whereby one of said gear trains can be rendered operative while the controlling clutch device of the other is in the operative position. 50
38. In a machine of the character described, a tool-carrying member, a frame having a way along which the member is movable, two separate driving shafts for said member, a separate gear train actuated by each shaft, for impelling the member along the way, a separate clutch device for rendering each gear train operative and inoperative as an impelling agent for the member, and an additional clutch mechanism, located in one of said gear trains, whereby the other gear train may be rendered operative, while the clutch device of the inoperative gear train is in the operative position. 55
39. In a machine of the character described, a frame having a way provided thereon, a tool-carrying member mounted on and movable along the way, a rack extending along the way, two separate gear trains mounted on the member, a rack-engaging pinion common to each train, a hand-wheel for actuating one of said gear trains, and a clutch mechanism between the hand-wheel and the pinion. 60
40. In a machine of the character described, a frame having a way provided thereon, a tool-carrying member mounted on and movable along the way, a feed drive shaft and a traverse drive shaft mounted on the frame, a feed drive mechanism mounted on the member and having an actuating hand-wheel located therein, a traverse drive mechanism located on the member, means for operatively connecting the feed drive mechanism to the feed drive shaft, means for operatively connecting the traverse drive mechanism to the traverse drive shaft, a clutch device located in said feed drive mechanism between the rack and the hand-wheel, and a single operating handle for controlling said clutch device and said means for operatively connecting the traverse drive mechanism to the traverse drive shaft. 65
41. In a machine of the character described, a frame having a way extending longitudinally thereof, a tool slide mounted on and movable along the way, a feed drive shaft journaled on the frame and extending 70

along the way, a feed drive mechanism mounted on said slide, and operatively connected to the feed drive shaft, a clutch device included in said feed drive mechanism, 5 a traverse drive shaft journaled on the frame and extending along the way, a reversing gear train mounted on the slide and operatively connected to the traverse drive shaft, a clutch mechanism for controlling 10 the operation of the reversing gear train, and for rendering the traverse drive shaft operative or inoperative as the driving agent of the slide, and a single means mounted on the slide for controlling the operation of 15 said clutch device and of said clutch mechanism, and for rendering one of said shafts inoperative as the driving agent of the slide when the other shaft is operative.

42. In a machine of the character described, a tool-carrying member, a frame having a way along which the member is movable, two separate gear trains mounted on the member and coöperating with the rack to impel the member along the way, a 20 hand-wheel operatively connected to one of said gear trains, a clutch device in the gear train, connected to the hand-wheel, and lo-

cated between the hand-wheel and the rack, a clutch device for controlling the operation of the other gear train, and a single operating handle for actuating both of said clutch devices to render one gear train operative and the other inoperative as the impelling agent of the member. 30

43. In a machine of the character described, a frame having a way, provided thereon, a tool-carrying member mounted on and movable along the way, two separate transmission mechanisms, mounted on the member, for impelling the member along 40 the way, a single means for rendering one mechanism operative and the other inoperative in moving the member, a hand-wheel operatively connected to one of said mechanisms and a clutch device located in the last- 45 mentioned mechanism between the hand-wheel and the operative connection of said mechanism to the frame.
